COMBINED NECKLACE AND BROOCH

Theodore C. Steinman, Purchase, N.Y., assignor to Accesscraft Products Corporation, New York, N.Y., a corporation of New York

Filed July 13, 1965, Ser. No. 86,142

Term of patent 3½ years

(Cl. D45—16)

FIG. 1

FIG. 2

FIG. 3

FIGURE 1 is a front perspective view of a combined necklace and brooch, showing my new design.

FIGURE 2 is a top plan view of the brooch alone.

FIGURE 3 is a rear elevational view of the brooch.

The portions of the link elements shown in full lines are repeated throughout the length of said elements as indicated by the broken line disclosure.

I claim:

The ornamental design for a combined necklace and brooch, substantially as shown and described.
